US00D746568S

(12) **United States Design Patent**
Piontkowski

(10) **Patent No.:** **US D746,568 S**
(45) **Date of Patent:** **** Jan. 5, 2016**

(54) **INSOLE PADS**

(71) Applicant: **Sharone Piontkowski**, New York, NY
(US)

(72) Inventor: **Sharone Piontkowski**, New York, NY
(US)

(**) Term: **14 Years**

(21) Appl. No.: **29/493,264**

(22) Filed: **Jun. 6, 2014**

(51) LOC (10) Cl. **02-04**

(52) U.S. Cl.

USPC **D2/961**

(57) **CLAIM**

The ornamental design for insole pads, as shown and described.

DESCRIPTION

FIG. 1 is a front perspective view of insole pads showing my new design;

FIG. 2 is a top view thereof;

FIG. 3 is a bottom view thereof;

FIG. 4 is a left side view thereof;

FIG. 5 is a cross sectional view taken along line 5-5 in FIG. 2;

FIG. 6 is a right side view thereof;

FIG. 7 is a front view thereof;

FIG. 8 is a cross sectional view taken along line 8-8 in FIG. 2;

FIG. 9 is a cross sectional view taken along line 9-9 in FIG. 2;

FIG. 10 is a back side view thereof;

FIG. 11 is a front perspective view thereof, shown in a used condition on a foot in broken lines;

FIG. 12 is a bottom view of FIG. 11;

FIG. 13 is a left side view of FIG. 11;

FIG. 14 is a right side view of FIG. 11;

FIG. 15 is a front view of FIG. 11; and,

FIG. 16 is a back side view of FIG. 11.

The broken lines shown in the drawings form no part of the claimed design.

1 Claim, 9 Drawing Sheets
